UNITED STATES PATENT OFFICE.

TRIMBLE DE ROODE, OF NEW YORK, N. Y.

COMBINED TYPE-WRITING AND PRINTING MACHINE.

1,224,121.

Specification of Letters Patent. Patented Apr. 24, 1917.

Application filed September 23, 1911. Serial No. 650,955.

To all whom it may concern:

Be it known that I, TRIMBLE DE ROODE, a citizen of the United States, residing at New York city, county and State of New

5 York, have invented certain new and useful Improvements in Combined Type-Writing and Printing Machines, of which the following is a full, clear, and exact description.

10 My invention relates to improvements in combined typewriting and printing machines, or machines which are particularly adapted to duplicate or turn out circular letters in the copies of which minor changes 15 occur such as in the address and in portions of the matter of the body of the letter.

A further object of my invention is to provide a machine upon which circular letters may be printed, in the main in duplicate, but in which not only the address may 20 be changed but also the body of the letter may be changed at any point at will.

A further object is to provide a device of this character which may be mounted 25 upon an ordinary typewriting machine after simply removing the platen thereof.

A further object is to provide means for indicating to the operator where the distinguishing matter is to be inserted.

30 A further object is to provide a duplicating mechanism which may be used alone or in combination with the typewriter, as desired.

A further object is to provide a machine 35 of this character in which the duplicating printing mechanism or duplicator and typewriting mechanism may print through the same ribbon, thus securing uniformity in the impressions.

40 A further object is to provide improved ribbon mechanism for a machine of this character.

A further object is to provide a construction in which the duplicating printing surface 45 may be raised from the paper when said surface is returning to starting position, or at any other period of the printing operation desired.

A further object is to provide a construction 50 in which the duplicating surface may be readily removed from the rest of the mechanism and a different surface substituted without removing the entire duplicating printing mechanism from the typewriting machine.

A further object is to provide means for securing uniformity of impression of long or short lines of type on the duplicating mechanism.

With these and other objects in view, as 60 will appear from the following specification, the invention consists in a construction and arrangement of parts, the preferred embodiment of which is illustrated in the accompanying drawings, in which,

65 Figure 1 is a side elevation of so much of an ordinary front-strike typewriting machine as is necessary to illustrate the invention, showing my improved duplicating mechanism mounted thereon.

70 Fig. 2 is a front elevation, part section, of the duplicating mechanism removed from the typewriting machine.

75 Fig. 3 is a plan view of the parts shown in Fig. 2.

Fig. 4 is a sectional view on the line 4—4, Fig. 3.

80 Fig. 5 is a view of the coöperating gears of the platen and type cylinder taken on the section line 5—5, Fig. 2.

Fig. 6 is a sectional detail of one of the bearings of the type cylinder.

Fig. 7 is a fragmentary longitudinal sectional view of the type cylinder detached.

Fig. 8 is a transverse sectional view of the 85 type cylinder.

Fig. 9 is an end elevation thereof.

Fig. 10 is a transverse sectional view of the type cylinder support.

Fig. 11 is a longitudinal sectional view 90 of the type cylinder support showing the shaft upon which it is mounted.

Fig. 12 is an end elevation of the type cylinder support.

Fig. 13 is a view in detail of the means 95 for securing uniformity of impression of long or short lines of type on the printing bed.

Fig. 14 is a detail of a backing strip for securing such uniformity, and

100 Fig. 15 is a view, similar to Fig. 14, of a strip of greater thickness.

In the embodiment of my invention herein selected for illustration,

105 1 indicates a portion of the main frame of an ordinary front-strike typewriting machine. 2 indicates the platen carriage mounted in the usual manner upon standards 3. 4 indicates one of the type bars which is mounted in any usual and desired 110

manner to operate upon a platen. The printing mechanism of the typewriter, however, may be of any desired construction, such as a type wheel, or otherwise. 5 is the ordinary spacing lever. The parts enumerated 5 may be of any desired style or construction, and while applicant's invention herein shown is applied to a front-strike machine, it is to be understood that broadly 10 it may be applied equally well to an under-strike or a top-strike machine.

In applying my invention to a front-strike machine, I employ a main frame comprising end plates 6 united by cross bars 7 and 8 respectively. One of the end plates, for example, that on the right hand side of the machine, as shown in Fig. 1, has a supporting standard 9 forked at 10 (Fig. 2) to embrace the forward extension 11 of the platen 15 carriage frame 2. This frame also has a standard 12 which is curved to rest upon the upper edge of the platen carriage frame and to extend down within the carriage frame to support and steady the printing mechanism 20 upon said carriage frame. In this construction it will be seen that the printing mechanism is supported and carried bodily by the platen carriage frame and partakes of its endwise feeding movement. This right 25 hand end plate 6 is also provided with a depending arm 13, and the opposite end plate 6 (Fig. 5) is provided with a downward extension 14, within which the shaft 15 of the duplicating platen 16 is journaled. 30 As hereinbefore stated, this platen is substituted in place of the usual typewriter platen. The left hand end frame 6 is also provided with an extension 17 which rests upon the left hand end frame of the platen carriage. Each of the end frames 6 is provided 35 with a rearward extension 18 in the extremities of which is mounted a ribbon carrying drum or roll 19, one spindle 19' on which is provided at one end with a gear 20 intermeshed with a gear 21 on a shaft 22 journaled in one of the rearward extensions 18, said shaft 22 also having a gear 23 adapted 40 to mesh with a gear 24 on a shaft 25 journaled in lateral projections of one of the end plates 26 of the printing cylinder frame. This printing cylinder frame is pivoted upon the forward cross bar 7 of the main duplicator carrying frame. Shaft 25 has a second gear 25' meshing with a gear 45 27' on the shaft of the printing cylinder 27.

The printing cylinder 27 is provided with a plurality of slots 28 within which the type 50 29 may be removably mounted by sliding them in from the ends of the cylinder. In order to mount the printing cylinder in operative position, I provide a cylinder support 60 consisting of segmental end members 30, Figs. 10, 11 and 12, which are fixed upon opposite ends of the cylinder shaft 31. Said 65 members are preferably united by a webbing

30'. Each of said supporting members is provided with a latch 32 adapted to engage locking slots 33 in the opposite ends of the printing cylinder. This cylinder is provided with a segmental opening 34 adapted to fit over the supporting members 30, and to be locked thereto to move therewith. Within the cylinder support are mounted the spring held bearing studs 35, upon and between which may be removably mounted a ribbon spool 36, which spool may be keyed to the studs 35 in any desired manner. The shaft 31 of the cylinder support is eccentrically mounted in bearing bushings 37 (Fig. 6) which in turn are carried by bearing blocks 38, slidingly mounted on guides 39 on the cylinder carrying frame 26. In order to adjust the printing cylinder to and from the platen, the bearing blocks 38 are provided with studs or pins 38' received within recessed studs 40, adjustably threaded in plates 41 secured to the frame 26. Within the recesses of the studs 40 may be placed resilient cushions 42 against which the upper ends of the studs 38' bear to effect resilient pressure of the printing cylinder 45 upon the platen.

The bearing blocks 38 are steadied within their guideways by springs 43 interposed between said blocks and frames 26. The cylinder shaft is provided with an operating crank handle 44 by which the printing cylinder may be revolved to effect the printing impression.

In Figs. 1 and 4, the printing cylinder is shown in initial position with respect to the platen, before the printing operation has been effected. In order to print, the cylinder, as viewed in Fig. 1, is rotated by the handle 44 in the direction contrary to the movements of the hands of a watch, it being understood that the cylinder is at such time properly spaced to bring the type carried thereby into printing contact with the platen.

The bearing bushings 37 are each provided with an arm 45, the right hand arm carrying a pin 46 and the left hand arm a pin 47, the pin 46 lying in the path of the crank handle 44, and the pin 47 in the path of an arm 48 secured to the printing cylinder shaft 31. By this construction, when the crank arm 44 is revolved from the position indicated in Fig. 1, it will, upon completing its revolution, strike the bushing operating pin 46, and thereby revolve its arm 45 to the rear. At the same time, the shaft arm 48 at the opposite end of the cylinder carrying shaft will strike the pin 47 and move its bushing arm 45 to the rear whereby the eccentric 115 bushings 37 will be revolved to raise the cylinder shaft 31 and the printing cylinder 120 away from the platen 16.

Adjacent to the pins 46 and 47 are provided stop springs 49 which serve to limit 130

the swing of the arms 45 and to hold said arms in the position to which they are thrown by the crank arm 44, and corresponding operating arm 48 of the cylinder shaft. These spring arms 49, in conjunction with the pins 46 and 47, determine the extent of movement of the printing cylinder in either direction.

From the above described construction it will be seen that while the printing cylinder is being returned to initial printing position, it is held free of the platen, but is moved toward the platen by the movement of the eccentric bushings at the end of the return stroke so that upon the next printing stroke the printing operation may be again effected.

In order to secure uniformity of impression by both the type of the printing cylinder and the type bars of the typewriting machine, I provide a single ribbon 50, Figs. 1 and 4, one end of which passes around a ribbon drum 19, and through a slot 51, into said drum where it is rolled upon the shaft or spool proper 52. The ribbon 50 is rolled twice around the ribbon carrying drum 19 for the purpose hereinafter described. The ribbon spool 52 is journaled in suitable bearings in the opposite ends or heads of the ribbon drum 19 so that said spool 52 may revolve independently of the rotation of said drum. As shown in Fig. 2, the ribbon spool 52 is engaged by a short shaft 53 having a crank handle 54 by which any slack may be taken up, it being understood that this shaft 53 revolves independently of the drum 19. The short shaft 53 is yieldingly held in operative position by means of a suitable spring 55, and said shaft may be moved longitudinally against the pressure of said spring whereby the shaft may be disengaged from the spool 52, and the ribbon drum thereupon removed from the machine. The ribbon 50 is led from the drum 19 between ribbon guides 56 and 57 secured to the end plates 6 of the printing mechanism supporting frame, said guides 56 and 57 passing beneath and partially around the platen 16. The forward ends of these guide plates may be arranged in any desired manner to properly guide the ribbon and paper around the platen. As here shown, the ribbon is carried between the guide plates, and, therefore, does not come in contact with the platen in its movement around the same. As shown in Fig. 2, the outer guide plate 57 is provided, opposite the printing line, with an opening 58 to permit impact of the type bars upon the platen at any desired point. The ribbon 50 passes through this opening 58 and passes to the ribbon spool 36 mounted in the printing cylinder support, as above described. The forward extremity of the inner guide plate may be provided with a shiftable paper guide finger 59 slidably mounted upon a rod

60 whereby the entire feeding edge of the sheet of paper is held snugly against the platen and is carried about the same and guided beneath a shield plate 61 mounted at the rear of the printing cylinder, as shown in Fig. 4. At the rear of the platen and printing cylinder also is provided a guide plate 62, between which and the guide plate 56 paper may be introduced to the platen. The guide plate 56 also may be provided with the usual pressure rolls 63 to hold the paper snugly against the platen. The guide plate 62 also forms a passage 62' with the shield 61 by which the paper is led out from the machine.

In operation, the desired subject matter of the body of the latter is set up on the type cylinder. The paper is then introduced and properly spaced to receive the salutation, which may be written in by means of the usual typewriting mechanism. In so writing, the type strikes through the ribbon 50. For the insertion of distinguishing matter in each circular letter, proper spaces are left between the type of the printing cylinder. When the printing, by means of the printing cylinder, has progressed to a point where it is necessary to insert the distinguishing matter, the latter is effected by operating the typewriting mechanism. In order to insure accurate insertion of the distinguishing matter to be printed, I provide a stop lug 29' which may be inserted in any of the type slots of the printing bed, in the type line in which matter is to be inserted, coöoperating with which is a stop 29² on rod 7, which stop is held in the path of the lug by a spring 29³ so that rotation of the cylinder will be positively stopped when these parts come into engagement. Stop 29² has a handle 29⁴ by which the stop may be released after the insertion has been made. I may also provide a guide finger 64 adjustably mounted on the rod 7 of the printing mechanism frame. When the space in the type matter of the type cylinder comes opposite this finger, the operator is advised that the typewritten matter is to be inserted; moreover, the inserting point may be indicated by type lugs 29⁵ of the distinguishing shape or color. From an inspection of the relative positions of the type cylinder and the platen, it will be seen that this typewritten matter is written in prior to the printing of the context of the line in which it appears in the letter, it being understood that the indicating finger 64 is positioned at the same distance from the point of impact of the printing cylinder type upon the platen as the point of impact of the type bars is separated from such first mentioned point of impact.

In practice, it is found that short lines of type give a heavier impression than long lines; therefore, to secure uniformity of impression of long and short lines of type on

a printing bed, I provide means such as backing strips 27^a and 27^b, Figs. 14 and 15, which may be slipped into the type slots 28 beneath the type 29 to elevate somewhat 5 the longer lines of type. These strips may be of different thicknesses to accord with the lengths of the lines. No strip is used under a short line, a thin strip is used under a line of medium length and a thicker strip 10 for a longer line.

As the type cylinder is revolved to effect the printing operation, the ribbon is drawn around the cylinder and over the forward extension of the inner ribbon guide plate 15 56, said guide plate terminating just in front of the point of impact of the type of the type cylinder, hence all danger of smudging the paper by the ribbon is avoided. As the type cylinder is revolved, 20 the ribbon drum 19 is simultaneously revolved through the train of gears and shafts 20 *et seq.* at a surface speed equal to that of the type cylinder. The diameter of the ribbon drum 19 is approximately one-half 25 that of the type cylinder so that the double wind of ribbon on the spool is exhausted at the moment the type cylinder reaches approximately the end of its printing stroke.

It is desirable that the position of the 30 ribbon relative to the platen and printing cylinder be slightly changed after each printing operation in order that subsequent operations may take place through different portions of the ribbon. For this purpose 35 one of the spring studs 35 within the type cylinder support, which carries the ribbon spool 36 within the type cylinder, is provided with a ratchet wheel 65 engaged by a spring pawl 66 carried by an arm 67 40 which in turn is pivoted upon the stud 35. As before stated, the ribbon spool 52 is frictionally mounted in the drum 19 and may revolve independently of the rotation of said drum. Just as the printing cylinder 45 reaches the end of its stroke, the arm 67 comes in contact with a suitable abutment pin 68 (Fig. 2) fixed to the machine frame, whereby the ribbon spool 36 is given a partial rotation within the printing cylinder, 50 thus taking up any slack of the ribbon in its path from its spool 52 to the spool 36, and drawing a slight excess of ribbon from the spool 52, it being understood that when the printing cylinder reaches approximately 55 the end of its printing stroke, the opening 51 in the drum 19 has reached approximately the point 69 (Fig. 4) where the ribbon leaves the drum. While the printing cylinder is being returned to initial position, 60 the ribbon drum 19 is reversed by the chain of gears above specified and the ribbon rewound thereon.

The printing cylinder is provided with a gear wheel 70 intermeshing with a gear 65 wheel 71 rotatably mounted on the shaft

15 of the platen, said gear wheel 71 being provided with a spring pawl 72 engaging a ratchet wheel 73 secured to the platen shaft. By this arrangement the platen is rotated positively at the same surface speed 70 as the printing cylinder during the printing stroke, whereas, the eccentric mounting of the printing cylinder shaft heretofore described is sufficient to maintain said gear wheels disengaged while the printing cylinder 75 is being returned to initial position. This ratchet and pawl arrangement of the platen also permits the platen to be rotated by the ordinary line spacing mechanism of the typewriting machine independently of the printing cylinder. For such independent spacing, the platen is provided with the usual spacing ratchet 74.

If at any time during the printing operation it is desirable to omit one or more 85 paragraphs set up on the printing cylinder, the pins 46 and 47 are moved by hand to raise the cylinder and its gear from engagement with the platen gear, and the cylinder then rotated until the undesirable paragraph or paragraphs have been moved 90 past the printing point, whereupon the pins are again moved to return the cylinder and platen gears into engagement, and the printing operation continued.

In order to mount the ribbon spool 36 within the printing cylinder and also for the purpose of facilitating inspection of the parts of the machine between the printing cylinder and the platen, the end plates 26 100 of the printing cylinder frame are pivoted upon the rod 7 whereby said cylinder may be moved to the position indicated in Fig. 1. Under such conditions also the gear wheel 24 is disengaged from the gear wheel 23 of the ribbon mechanism and consequently the ribbon spools may be independently rotated to take up slack of the ribbon and to properly adjust the same in the machine.

In some cases it may be desirable to use 105 a duplicating mechanism alone. To this end I provide the end plates 6 with feet 6' upon which the duplicating mechanism alone may be set up on a table or bench.

While I have herein described a preferred embodiment of my invention, it is to be understood that the same may be altered in detail and arrangement of parts within the scope of the appended claims.

What I claim is:

1. In a typewriting and printing machine, the combination of a typewriting mechanism including a platen with which the type of the mechanism coact, a printing surface mounted in position to coöperate 125 with said platen and capable of supporting type characters at any point thereon in position to coact with the platen, said typewriting mechanism being operable at an intermediate point in the operation of print- 130

ing from said printing surface, and means for securing alinement of the typewritten and printed matter.

2. In a typewriting and printing machine, the combination of a typewriting mechanism including a platen with which the type of the mechanism coact, a printing surface mounted in position to coöperate with said platen, said typewriting mechanism being operable at an intermediate point in the operation of printing from said printing surface and irrespective of the arrangement of the printing characters upon the printing surface, and means for securing alinement of the typewritten and printed matter.

3. In a typewriting and printing machine, the combination of a typewriting mechanism including a rotatable platen with which the type of the mechanism coact, a printing surface mounted in position to coöperate with said platen and capable of supporting type characters at any point thereon in position to coöperate with the platen, a ribbon mounted adjacent to the platen to supply ink for printing both from said type and from said printing surface, said typewriting mechanism being operable during and while temporarily suspending the operation of printing from said printing surface, and means for securing alinement of the typewritten and printed matter.

4. In a typewriting and printing machine, the combination of a typewriting mechanism including a rotatable platen with which the type of the mechanism coact, a printing surface mounted in position to coöperate with the platen, a ribbon mounted in position to supply ink for printing from said type and from said printing surface, said typewriting mechanism being operable at an intermediate point in the operation of printing from the printing surface and irrespective of the arrangement of the printing characters upon the printing surface, and means for securing alinement of the typewritten and printed matter.

5. In a typewriting and printing machine, the combination of a typewriting mechanism including a platen with which the type of the mechanism coact, a printing surface mounted in position to coöperate with the platen, said typewriting mechanism being operable during and while temporarily suspending the operation of printing from the printing surface, and shiftable indicating means for indicating the insertion of typewritten matter in the body of the matter printed from said printing surface.

6. In a typewriting and printing machine, the combination with a platen and typewriting mechanism, of a printing surface coöoperating with said platen, and shiftable means for indicating and positively stopping the printing operation at the point or points at which typewritten matter is to

be inserted in the body of the printed matter.

7. In a typewriting and printing machine, the combination of a typewriting mechanism including a cylindrical platen with which the type of said mechanism coact at a predetermined portion thereof, a printing surface mounted in position to coöperate with the platen at a predetermined portion thereof displaced circumferentially of the platen from the portion with which the type of the typewriting mechanism coact, said typewriting mechanism being operable at an intermediate point in the operation of printing from said printing surface, and means for securing alinement of the typewritten and printed matter.

8. In a typewriting and printing machine, the combination with a platen and typewriting mechanism coöoperating therewith, of a rotary printing surface also coöoperating with said platen, ribbon mechanism, including a single ribbon, through which both the typewriting and printing impressions may be effected, and means to operate the said ribbon mechanism through the rotation of said printing surface.

9. In a typewriting and printing machine, the combination of a platen, a typewriting mechanism coöoperating therewith, a printing surface adapted to coöperate with the platen, a ribbon extending around the platen, means for feeding the ribbon around the platen during the operation of printing from the printing surface, and a guard for holding the ribbon out of contact with the platen at portions of the platen where no impression is taken.

10. In a typewriting and printing machine, the combination with a platen and typewriting mechanism coacting with the platen at an impression point thereon, of a printing surface also coöoperating with said platen at an impression point thereon, a ribbon mechanism including a single ribbon extending around the platen, means for feeding the ribbon around the platen and past the impression points where the typewriting mechanism and the printing surface coact with the platen, and a guard curved about the platen for maintaining the ribbon out of contact with the paper except at the said impression points.

11. In a typewriting and printing machine, the combination of a platen, a typewriting mechanism coacting therewith, a printing surface, means for moving the printing surface in coaction with the platen to effect the printing and for returning the printing surface to initial position, and means for automatically moving the printing surface and platen relatively out of co-operative relation after the printing movement and prior to the return movement of the printing surface.

12. In a typewriting and printing machine, the combination with a platen and typewriting mechanism therefor, of a printing cylinder mounted adjacent said platen, 5 means for rotating said cylinder in one direction to effect printing impression against said platen, and for reversing the rotation of said cylinder, and means for maintaining said cylinder out of contact with said platen during said reverse movement.

13. In a typewriting and printing machine, the combination of a frame having supports thereon for a removable platen, a typewriting mechanism mounted on the 15 frame in position to coact with a platen mounted on said supports, and a printing machine comprising a printing surface and a platen with which the printing surface co-operates, said printing machine being removably mounted on the frame with its 20 platen in the position of a platen mounted on said supports.

14. In a typewriting and printing machine, the combination of a frame, a carriage 25 movable thereon and adapted to sustain a removable platen, a typewriting mechanism mounted on the frame in position to co-operate with the platen on said carriage, and a printing machine removably mounted on 30 said carriage and consisting of an auxiliary frame, a printing surface mounted on the auxiliary frame, and a rotatable roller platen also mounted on the auxiliary frame and adapted to coact with the printing surface to effect printing.

15. In a typewriting and printing machine, the combination of a frame, a carriage movable thereon and adapted to sustain a removable platen, a typewriting mechanism 40 mounted on the frame in position to co-operate with the platen on the carriage at a printing point on the platen, and a printing machine removably mounted upon said carriage, said printing machine consisting of 45 an auxiliary frame, a printing surface mounted thereon, a cylindrical roller platen mounted for rotation upon the auxiliary frame and adapted to coact with the printing surface at a printing point thereon, and 50 an ink ribbon also mounted on the auxiliary frame and extending over the printing points of the printing surface and the typewriting mechanism upon said platen.

16. In a typewriting and printing machine, the combination with a platen carriage and typewriting mechanism of a typewriting machine, of a printing mechanism comprising a frame adapted to be mounted on said platen carriage, and a platen, printing surface and ribbon mechanism mounted 55 on said frame, said parts being so constructed and arranged that printing impressions may be effected against said platen both by the typewriting mechanism and said 60 printing surface.

17. The combination with a typewriting machine having a platen carriage, of a duplicating printing mechanism comprising a frame adapted to be mounted on said platen carriage when the typewriting platen is removed, and a platen, duplicating printing surface, and ribbon mechanism carried by said frame, said parts being so constructed and arranged that printing impressions may be effected against the platen through the same ribbon, both by the typewriting mechanism and by said duplicating printing surface.

18. In a typewriting and printing machine, the combination of a typewriting machine having its platen removed, and a self-contained duplicating apparatus mounted upon and moving with the platen carriage thereof, said apparatus comprising a platen adapted to be substituted in the place of the typewriter platen, and a duplicating printing surface and ribbon mechanism co-operating therewith, said parts being so constructed and arranged that printing impressions may be effected against said platen through the ribbon of said ribbon mechanism by both the typewriting machine and by the printing surface of said duplicating apparatus.

19. In a combined typewriting and printing machine, the combination with a platen carriage, of a frame adapted to be removably mounted on said carriage, said frame having a platen, printing surface, and ribbon mechanism mounted therein, said ribbon mechanism including a ribbon having one end carried by said printing surface, and the opposite end carried by said frame, and means whereby said ribbon may be caused to travel over said platen coincidently with the printing movement of the printing surface, and may be returned to initial position by the return movement of said printing surface, and means whereby said ribbon may be shifted relatively to said platen and printing surface at the end of the return movement of said surface.

20. In a typewriting and printing machine, the combination with a platen carriage and a typewriting mechanism, of a frame adapted to be removably mounted on said platen carriage, said frame having a platen, a printing cylinder and ribbon mechanism mounted thereon, said parts being so constructed and arranged that printing impressions may be effected against said platen through said ribbon both by the typewriting mechanism and the printing cylinder, said ribbon mechanism including a ribbon spool mounted within said printing cylinder, and a ribbon spool mounted on said frame, and a ribbon attached to said spools respectively, and adapted to be fed past the platen by the printing revolution of said printing cylinder and to be positively returned to initial posi-

- tion by the return revolution of said printing cylinder, said typewriting mechanism and printing cylinder being so relatively arranged that all impressions are effected 5 against said platen through said ribbon.
21. In a typewriting and printing machine, the combination with a platen carriage and typewriting mechanism, of a platen mounted on said carriage, a printing cylinder support also mounted on said carriage, a printing cylinder removably mounted on said support, whereby different printing cylinders may be interchanged in said machine, a ribbon mechanism including a 10 ribbon adapted to be fed past said platen whereby printing impressions may be effected through said ribbon, both by the typewriting mechanism and said printing cylinder.
- 20 22. In a typewriting and printing machine, the combination with a platen and typewriting mechanism, of a printing cylinder support adjacent said platen, a ribbon spool carried by said support and a ribbon 15 spool carried independently of said support, a ribbon connected with each of said spools respectively, a printing cylinder adapted to be removably mounted on said support and to coöperate with said platen, and means for 25 feeding said ribbon over said platen whereby printing impressions may be effected through said ribbon both by said typewriting mechanism and by said printing cylinder.
- 30 23. In a typewriting and printing machine, the combination with a platen carriage and typewriting mechanism, of a frame adapted to be mounted on said carriage, a platen carried by said frame, a 35 printing cylinder carrying frame pivoted to said first mentioned frame, a ribbon mechanism comprising a ribbon spool carried by said main frame and a ribbon spool carried by said printing cylinder carrying frame, 40 said parts being so constructed and arranged that said printing cylinder may be swung free of said platen without disturbing the other parts of the machine.
24. In a duplicating machine, the combination of a frame, a cylindrical platen thereon, a typewriting mechanism mounted 45 on the frame and coacting with the platen at a predetermined point thereon, a printing surface mounted on the frame in position to have its type characters coöperate with the platen one line at a time at a point on the platen displaced circumferentially of the platen from the point of coaction of the type of the typewriting mechanism with the 50 platen and means for securing alinement of the typewritten and printed matter.
- 55 25. In a duplicating machine, the combination of a frame, a platen carriage thereon, a platen on the carriage, a typewriting mechanism on the frame coöoperating with the platen at a predetermined point thereon, a printing surface mounted on the carriage and coöperating with the platen at a point on the platen displaced from the point of coaction of the type of the typewriting mechanism with the platen, and means for 55 securing alinement of the typewritten and printed matter.
- 60 26. In a duplicating machine, the combination with a platen and typewriting mechanism coöperating therewith, of a printing bed also coöperating with said platen, said printing bed and typewriting mechanism operating at different points against said platen, means for alining the 65 typewritten and printed matter, and means for varying the alinement of the typewritten and printed matter.
27. In a duplicating machine, the combination of a frame, a platen carriage thereon, a platen on the carriage, a typewriting mechanism on the frame coöperating with the platen at a predetermined point thereon, a printing surface mounted on the carriage, means for operating the printing surface to 75 cause the same to coöperate with the platen at a point on the platen displaced from the point of coaction of the type of the typewriting mechanism, and means for securing alinement of the typewritten and printed 80 matter.
28. In a combined typewriting and printing machine, a frame, a platen mounted thereon, typewriting mechanism mounted on the frame and coöperating with the 85 platen, a type-supporting member also mounted on the frame in coöperative relation to said platen, type supported on said member in lines, and means for raising individual lines of said type to different 90 heights to vary the pressure of the type against the platen.
29. In a typewriting and printing machine, the combination of a frame, a printing couple mounted on the frame and consisting of a cylindrical platen and a printing surface, a typewriting mechanism mounted on the frame and provided with type levers, the type of which are adapted to coact with the front portion of the platen, an ink ribbon 95 extending about the platen for coaction with the printing ribbon surface and typewriting mechanism and means for moving the printing surface from the front of the machine toward the rear thereof in coaction with the 100 platen to print from the printing surface by a rolling motion, whereby the portion of the printing surface approaching the printing point of the printing surface upon the platen is visible to the operator.
30. In a typewriting and printing machine, the combination of a frame, a platen mounted thereon, a typewriting mechanism mounted on the frame and provided with 105 type-levers, the keys of which are adapted to 110
- 65 120 125 130

coact with the forward portion of the platen, a printing surface mounted on the frame, an ink ribbon mounted for coaction with the printing surface and platen, and 5 means for moving the printing surface in coaction with the platen in a direction from the front toward the rear of the machine, whereby the portion of the printing surface approaching the printing point of the printing surface upon the platen is visible to the 10 operator.

31. In a combined typewriting and printing machine, a typewriting machine provided with an inking ribbon, a printing 15 mechanism provided with a platen rotating against the printing surface thereof, and means whereby said printing surface may be moved away from said platen so as to render visible the matter already printed or 20 typewritten.

32. In a combined typewriting and printing machine, a typewriting machine provided with an inking ribbon, a printing mechanism provided with a platen rotating 25 against the printing surface thereof, and means whereby said platen and printing surface may be separated on a line radial to said platen at the point of printing contact to expose the printed matter to view.

33. In a typewriting and printing machine, a frame, a typewriting mechanism including a ribbon mounted thereon, a platen also mounted on the frame and coacting with the typewriting mechanism, and a 35 printing surface mounted on the frame in position to coact with the platen and capable of supporting printing characters at any point thereon, said printing surface being so constructed as to permit of rendering any 40 selected portion thereof operative or inoperative irrespective of the dimensions of such portion, and said typewriting mechanism being operative at intermediate points in the operation of printing from the printing 45 surface while that operation is temporarily suspended, which intermediate points correspond to the inoperative positions of the printing surface.

34. In a duplicating machine, a frame, a 50 typewriting mechanism thereon, a carriage, a platen mounted on the carriage, a type-carrying cylinder mounted on the carriage in position for coaction with the platen, an ink-ribbon having one end thereof mounted 55 upon the type-carrying cylinder, said ribbon extending partially around the platen, and a hollow spool having a slot therein mounted upon the carriage, said ribbon having its opposite end rolled and lying within the 60 spool, the portion of the ribbon adjacent to said rolled end extending through said slot and around the spool.

35. In a duplicating machine, the combination with a platen and a printing 65 surface coöperating therewith, of ribbon mecha-

nism comprising a ribbon constructed and arranged to be operated by the movement of said surface, a hollow spool carrying one end of said ribbon and within which said ribbon is rolled, said ribbon being led out of said spool and given one or more turns around the periphery thereof, and extended thence across the printing point whereby said ribbon may be fed uniformly at each printing operation.

36. A duplicating machine comprising a platen, a printing surface coöperating therewith, a ribbon mechanism comprising a ribbon interposed between said platen and surface means for feeding said ribbon, a frame carrying said parts, said frame having means whereby it may be mounted upon the carriage of a typewriting machine, and having means whereby it may be supported in operative position independently of said typewriting machine.

37. In a duplicating machine, the combination with a platen and a printing surface coöperating therewith, of ribbon mechanism comprising a ribbon interposed between the platen and surface, means for feeding said ribbon, and a frame for said parts having means whereby said machine may be supported in one position upon the carriage of a typewriting machine in coöperation with said typewriting machine, said frame having also means whereby said duplicating machine may be supported in a different operative position independently of said typewriting machine.

38. In a typewriting and printing machine, the combination of a frame, a platen, thereon, a typewriting mechanism mounted on the frame and coacting with the platen, a printing surface mounted on the frame and movable in one direction in coaction with the platen and in the opposite direction to return to initial position, and means actuated automatically on completion of the movement of the printing surface in one direction for moving the platen and printing surface relatively to an inoperative relation.

39. In a typewriting and printing machine, the combination of a frame, a platen thereon, a typewriting mechanism supported on the frame and coacting with the platen, a printing surface capable of supporting type characters thereon mounted upon the frame and movable in one direction in coaction with the platen and in the opposite direction to return to initial position, and means actuated automatically on completion of the movement of the printing surface in one direction for moving the platen and printing surface relatively to an inoperative relation, said typewriting mechanism being operable at intermediate points in the operation of printing from the printing surface.

40. In a typewriting and printing machine, the combination of a frame, a typewriting mechanism supported thereon, a carriage movable upon the frame, a cylindrical platen mounted on the carriage in position for coaction with the typewriting mechanism, a type-holder adapted to have type arranged thereon in rows mounted on the carriage in position to coact with the platen 5 at a portion thereof displaced circumferentially from the portion coacting with the typewriting mechanism by such an amount as to insure alinement of the typewritten and printed characters, and means for moving the type-holder and platen in coaction to effect printing from the type of the type-holder.
- 10 41. In a typewriting and printing machine, the combination of a frame, a typewriting mechanism supported thereon, a carriage movable upon the frame, a cylindrical platen mounted on the carriage in position for coaction with the typewriting mechanism, a type-holder provided with 15 channels for the reception of rows of type mounted on the carriage in position to coact with the platen at a portion thereof displaced circumferentially from the portion of the platen coacting with the typewriting 20 mechanism by such an amount as to secure alinement of the typewritten and printed characters, means for moving the type-holder and platen relatively to effect printing from the type of the type-holder, and a 25 single ribbon coacting with both the typewriting mechanism and the type of the type-holder and having one end thereof mounted on the type-holder.
- 30 42. In a typewriting and printing machine, the combination of a frame, a typewriting mechanism mounted thereon, a rotatable platen mounted on the frame in position to coact with the typewriting mechanism, a rotatable type cylinder mounted on 35 the frame and provided with means for holding type in position for coaction with said platen, and means for causing simultaneous rotation of the platen and type cylinder to print from the type by rolling 40 motion of the type cylinder and platen.
- 45 43. In a combined typewriting and printing machine, the combination of a frame, a cylindrical platen mounted thereon, a typewriting mechanism mounted on the frame and coacting with the platen at a point on 50 the forward portion thereof, a printing surface mounted on the frame in position to
- coact with the platen at a point thereon displaced circumferentially from the point of coaction of the type of the typewriting mechanism by such an amount as to insure registration of the typewritten and printed characters, and means for moving the printing surface in a direction from the front toward the rear of the machine whereby the portion of the printing surface approaching the printing point of the printing surface upon the platen is visible to the operator. 60
- 55 44. In a combined typewriting and printing machine, the combination of a frame, a cylindrical platen mounted thereon, a typewriting mechanism mounted on the frame and coacting with the platen at one point thereon, a printing surface mounted on the frame in position to coact with the platen at another point thereon displaced circumferentially of the platen from the point of coaction of the typewriting mechanism with the platen by such an amount as to insure registration of the typewritten and printed characters, and an ink ribbon extending around the platen and coacting with both the typewriting mechanism and the printing surface. 70
- 60 45. In a combined typewriting and printing machine, the combination of a frame, a platen thereon, a typewriting mechanism mounted on the frame and coacting with the platen, a printing surface mounted upon the frame for reciprocatory movement and adapted to coact with the platen, means for reciprocating the printing surface, and means for automatically moving the platen and printing surface relatively so that they will coact during movements of the printing surface in one direction and will be out of coaction during movements of the printing surface in the opposite direction. 80
- 65 46. In a combined typewriting and printing machine, the combination of a frame, a platen thereon, a typewriting mechanism mounted on the frame and coacting with the platen, a printing surface mounted on the frame, movable back and forth thereon, and adapted to coact with the platen during its movement in one direction, and means for automatically moving the platen and printing surface relatively so that they will be out of coaction during movements of the printing surface in the opposite direction. 90

TRIMBLE DE ROODE.

Witnesses:

E. E. MORSE,
K. P. QUIRKE.

It is hereby certified that in Letters Patent No. 1,224,121, granted April 24, 1917, upon the application of Trimble de Roode, of New York, N. Y., for an improvement in "Combined Type-Writing and Printing Machines," an error appears in the printed specification requiring correction as follows: Page 7, line 117, claim 29, strike out the word "ribbon"; and that the said Letters Patent should be read with this correction therein that the same may conform to the record of the case in the Patent Office.

Signed and sealed this 29th day of May, A. D., 1917.

[SEAL.]

F. W. H. CLAY,

Acting Commissioner of Patents.

Cl. 101--181.
